Ivo Barbaresi, Florence, Italy, assignor to Salvatore Ferragamo S.p.A., Florence, Italy

Filed Feb. 12, 1969, Ser. No. 15,742

Claims priority, application Italy Aug. 22, 1968

Term of patent 7 years

Int. Cl. D2—04

U.S. Cl. D2—325

FIG. 1

FIG. 2

FIG. 4

FIG. 3

FIG. 1 is a side elevational view of a heel for a lady's shoe, showing my new design;
FIG. 2 is a bottom plan view thereof;
FIG. 3 is a rear elevational view; and
FIG. 4 is a side perspective view.

I claim:

The ornamental design for a heel for lady's shoe, substantially as shown.
